Primary Examiner — Jennifer L Watkins*Assistant Examiner* — John Patrick G Ribay(74) Attorney, Agent, or Firm — Dunlap Bennett & Ludwig, PLLC; Anna L. Kinney(57) CLAIM

The ornamental design for a hand-shaped handbag, as shown and described.

DESCRIPTION

FIG. 1 is a top front perspective view of a hand-shaped handbag, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings depict portions of the article that form no part of the claimed design.

1 Claim, 4 Drawing Sheets(56)
